Fig. 3

FIG. 1 is a perspective view of a tire embodying my new design, it being understood that the full line portions are repeated throughout the circumference of the tire shown by means of broken lines;

FIG. 2 is a fragmentary plan view of the full line portion of FIG. 1 on an enlarged scale;

FIG. 3 is a section in perspective taken on line 3—3 of FIG. 2;

FIG. 4 is a section taken on line 4—4 of FIG. 2 on a further enlarged scale;

FIG. 5 is a section taken on line 5—5 of FIG. 2 on a further enlarged scale.

The dominant features of my design reside in the full-line portions of the drawing.

I claim:

The ornamental design for a tire, as shown and described.
